Primary Examiner — Mary Ann Calabrese*(74) Attorney, Agent, or Firm* — Birch, Stewart, Kolasch & Birch, LLP(57) **CLAIM**

The ornamental design for a shelf for television receiver, as shown and described.

DESCRIPTION

1. Shelf for television receiver
  - 1.1 : Perspective
  - 1.2 : Rear perspective
  - 1.3 : Front
  - 1.4 : Back
  - 1.5 : Left
  - 1.6 : Right
  - 1.7 : Top
  - 1.8 : Bottom
  - 1.9 : Perspective, in a state of use with environment
- The broken lines shown in figure 1.9 depict environment of the shelf for television receiver that forms no part of the claimed design, the environment including a television on a wall and a sound bar on the shelf for television receiver.
